UNITED STATES PATENT OFFICE.

WILLIAM F. HUTHER, OF CANTON, OHIO.

RAIL-CLAMPING DEVICE.

Application filed February 24, 1927. Serial No. 170,498.

The invention relates to means for clamping railroad rails upon the ties; and the object of the improvement is to provide a device comprising a pair of clamping members 5 provided with jaws for engaging over the base flange of the rail and arms for extending beneath the base flange, a wedge being provided between the under side of the base and the arms for clamping the jaws tightly 10 upon the base, and having means for holding the wedge in adjusted position.

An embodiment of the invention is illustrated in the accompanying drawing, in which

15 Figure 1 is a transverse sectional view through a rail attached to a tie with the improved clamping device, taken substantially on the line 1—1, Fig. 2;

Fig. 2, a top plan view of a tie adapted to 20 accommodate the clamping device;

Fig. 3, a section substantially on the line 3—3, Fig. 2, showing the rail clamped in position upon the tie;

Fig. 4, a detached perspective view of one 25 of the clamping members;

Fig. 5, a similar view of a slightly modified form of clamping member;

Fig. 6, a transverse sectional view through 30 an I-beam tie, showing a modified form of clamping device for use thereon, and

Fig. 7, a fragmentary section, showing a modified form of clamping member.

Similar numerals refer to similar parts 35 throughout the drawing.

In Figs. 1 to 4 inclusive the invention is illustrated as adapted to use upon a tie 1 provided with a socket or slot 2 to receive the clamping device. When made of reinforced concrete, as shown in Figs. 1 and 2, 40 the slot or socket of the tie is lined with a pressed steel housing as illustrated.

The slot 2 is provided with the central enlargement 3 and is recessed at the bottom as shown at 4. The upper surface of the tie 45 may be grooved transversely as shown at 5 to receive the base flange 6 of the rail shown generally at 7.

Each of the clamping members 8 is provided at its lower end with a boss 9 of greater length than the width of the reduced portion of the slot 2 and adapted to be inserted through the enlarged central portion 3 of the slot and then moved back against one end 50 of the recessed lower portion 4.

55 The upper end of each clamping member is provided with the inturned jaw 10, ar-

ranged to bear upon the upper surface of the base flange 6 of the rail, and an angular arm 11 is spaced beneath said jaw and preferably provided with the tapered extremity 12.

For the purpose of drawing the clamping jaws 10 tightly down upon the base flange of the rail, a wedge plate 13 is provided to be driven between the under side of the base flange and the arms 11 of the clamping members. By driving this wedge plate into position, as shown in Figs. 1 and 3, the arms 11 are forced downward, causing the jaws 10 to tightly grip the base flange, clamping the same upon the top of the tie.

In order to hold the wedge plate in position, the under surface thereof may be provided with the ratchet teeth 14, near the narrow end of the wedge, for engagement with the pawl 15 which is located within the socket 16 in the upper surface of the tie.

In order to provide for driving the wedge from either side of the tie as desired, one of these sockets may be formed near each side edge of the tie as shown in Fig. 2, whereby the pawl may be placed in either socket as desired.

As the wedge is driven into place the bosses 9, at the lower ends of the clamping members, will be forced backward and upward into the position best shown in Fig. 1, abutting the ends and upper sides of the recessed portion 4 of the slot in the tie and the clamping members will thus pivot upon these bosses as they are driven into clamping position by the wedge.

The tie illustrated in Figs. 1 to 3 may be of cement or concrete as shown and provided with a metal lining 17 in the slot or this tie may be formed of wood, cast steel or the like if desired.

In Fig. 5 is shown a slightly modified form of the clamping member in which the lower end thereof is provided with an aperture 18 to receive a bolt 19 or the like instead of providing the boss at this point.

In Fig. 6 is shown an application of the clamping member to an I-beam tie 1^a in which the upper portion of the tie is slotted as shown at 2^a, the clamping member 8^a having the bifurcated portion 20 adapted to be connected to the web of the tie as by the bolt 21.

From the above it will be seen that spikes and the like are entirely dispensed with and the rails are held rigidly clamped to the ties and prevented from accidental loosening or

displacement, it being necessary to insert a tool beneath the wedge plate to disengage the pawl from the ratchet teeth thereon before the wedge plate can be withdrawn and 5 the clamping members disengaged from the rail.

As illustrated in Fig. 7, the construction may be slightly modified, each clamping member being provided with the curved or 10 angular extremity 22 adapted to pivot within the recess 23, the action of the apparatus being otherwise the same as described above.

I claim:

1. In combination with a tie provided with 15 a slot, and a rail, a clamping device including a pair of clamping members arranged to enter the slot in the tie, a jaw upon each clamping member arranged to engage the rail, an arm upon each clamping member 20 arranged to be located beneath the rail and a wedge plate arranged to be located between the rail and said arms.

2. In combination with a tie provided with a slot, and a rail, a clamping device including 25 a pair of clamping members arranged to enter the slot in the tie, a jaw upon each clamping member arranged to engage the rail, an arm upon each clamping member arranged to be located beneath the rail, a 30 wedge plate arranged to be located between the rail and said arms, and means for locking said wedge plate in position.

3. In combination with a tie provided with a slot, and a rail, a clamping device including 35 a pair of clamping members arranged to enter the slot in the tie, a jaw upon each clamping member arranged to engage the rail, an arm upon each clamping member arranged to be located beneath the rail, a 40 wedge plate arranged to be located between the rail and said arms, teeth upon said wedge plate and a pawl upon the tie for engaging the teeth to lock the wedge plate in position.

4. In combination with a tie provided with 45 a slot, and a rail, a clamping device including a pair of clamping members arranged to enter the slot in the tie, a jaw upon each clamping member arranged to engage the rail, an arm upon each clamping member 50 arranged to be located beneath the rail, a

wedge plate arranged to be located between the rail and said arms, teeth upon said wedge plate and a pawl mounted in a socket in the tie for engaging the teeth to lock the wedge plate in position.

55

5. In combination with a tie and a rail, a clamping device including a pair of clamping members arranged for pivotal engagement with the tie, a jaw upon each clamping member arranged to engage the rail, an arm upon each clamping member arranged to be located beneath the rail and a wedge plate arranged to be located between the rail and said arms.

6. In combination with a tie and a rail, a 65 clamping device including a pair of clamping members arranged for pivotal engagement with the tie, a jaw upon each clamping member arranged to engage the rail, an arm upon each clamping member arranged to be located beneath the rail, a wedge plate arranged to be located between the rail and said arms and means for locking said wedge plate in position.

7. In combination with a tie and a rail, a 75 clamping device including a pair of clamping members arranged for pivotal engagement with the tie, a jaw upon each clamping member arranged to engage the rail, an arm upon each clamping member arranged to be located beneath the rail, a wedge plate arranged to be located between the rail and said arms, teeth upon said wedge plate and a pawl upon the tie for engaging the teeth to lock the wedge plate in position.

85

8. In combination with a tie and a rail, a clamping device including a pair of clamping members arranged for pivotal engagement with the tie, a jaw upon each clamping member arranged to engage the rail, an arm upon each clamping member arranged to be located beneath the rail, a wedge plate arranged to be located between the rail and said arms, teeth upon said wedge plate and a pawl mounted in a socket in the tie for 90 engaging the teeth to lock the wedge plate in position.

95

In testimony that I claim the above, I have hereunto subscribed my name.

WILLIAM F. HUTHER.
